UNITED STATES PATENT OFFICE.

WILLIAM YOULTEN, OF HOVE, ENGLAND, ASSIGNOR TO HARRY SEYMOUR FOSTER, OF WESTMINSTER, ENGLAND, AND LOUIS NAPOLEON SCHOENFELD, OF HOVE, ENGLAND.

MACHINE FOR OPENING AND CLEANING COTTON, WOOL, AND OTHER FIBERS.

Application filed March 2, 1921. Serial No. 449,206.

To all whom it may concern:

Be it known that I, WILLIAM YOULTEN, a subject of the King of Great Britain and Ireland, residing at Hove, in the county of 5 Sussex, England, have invented certain new and useful Improvements in or Relating to Machines for Opening and Cleaning Cotton, Wool, and Other Fibers; and I do hereby declare the following to be a full, clear, and 10 exact description of the invention, such as will enable others skilled in the art to which it appertains to make and use the same.

This invention relates to machines for cleaning cotton, wool and other fibers.

15 With machines of the class in question it is usual to provide valves or their equivalents for controlling the admission of the base or fiber to be treated and the discharge of the treated product and it is a matter of 20 great importance to control these valves so that the material to be treated is admitted to the machine at proper intervals of time, and the product discharged at proper corresponding periods.

25 The object of my present invention is to provide apparatus automatically controlled, preferably from the cleaning machine itself, which apparatus causes the valves to be properly opened at appropriate intervals of 30 time and in proper sequence according to the nature and condition of the base material under treatment, the apparatus being moreover so constructed that the timing or period of treatment can be easily varied and regulated with great accuracy.

The automatic controlling apparatus forming the subject of my invention, comprises broadly a self contained change speed gear or mechanism from which the base and 40 and (or) product valves of the machine are controlled through suitable transmission members, convenient means for bringing any gear wheel or its equivalent in the change speed mechanism into gear with a shaft or 45 its equivalent in the controlling apparatus driven from a main shaft of the principal machine or from some other suitable source of power, preferably with means such as a stepped or coned pulley on the shaft of the 50 controlling apparatus by means of which such shaft is driven from the main or other shaft as aforesaid, in order, where desired

to give a greater range or scope for timing and adjusting purposes.

In order that my invention may be more 55 clearly understood I will now describe one particular automatic apparatus adapted for use with a machine for cleaning cotton, wool or other fiber, for instance of the type comprising a chamber in which the material to 60 be treated is beaten and blown by means of blades or their equivalent carried by a rotating shaft.

I provide a suitable dust tight casing, which I term the "magazine of gears." 65 Within this magazine upon a suitable shaft or spindle is mounted a series of various sized toothed wheels, the number and dimensions of which are selected according to the various speeds required. 70

I also provide a driving shaft for the apparatus, which is driven by means of a stepped pulley or coned pulley by a belt or other transmission mechanism from the main shaft or other appropriate source of 75 power.

Suitably mounted within the casing is a pivotally mounted bracket or lever. This bracket carries an idle pinion, which is adapted, when the lever is slidden and rocked 80 into various positions to mesh with any of the gear wheels of the magazine and the idle wheel is in permanent gear with a pinion which is driven by the shaft of the apparatus, the construction being such that the 85 lever can be rocked over and set into such a position that the rotary motion can be transmitted from the shaft through the sliding pinion and the idle pinion to any required wheel in the magazine. 90

Suitable means, such as a pin or stud is provided for locking the lever in the required position.

The shaft carrying the gear wheels is formed with, or has connected thereto a 95 worm, suitably housed in the casing, appropriate thrust bearings or the like being used.

This worm gears with a worm wheel having a given number of teeth, for instance 60, representing 60 seconds to the minute. 100

On each side of the worm wheel is an extended boss and upon each of these bosses is mounted a wheel or disc.

These wheels or discs I term the index

wheels and each of them is of the same pitch diameter as the worm wheel. They are fixed to the bosses so that they rotate at the same speed as the worm wheel, and from one unit.

The index wheels gear or register with a pinion mounted upon a separate shaft or axle, and a suitable cranked or equivalent mechanism is fitted at each end of the shaft 10 to produce a reciprocating motion in rods connected therewith.

The two index wheels and corresponding pinions are constructed and arranged to work as a stop and start motion at various 15 positions of their circumference.

In the preferred construction each index wheel is of the same pitch diameter as the worm wheel and may be taken to represent 20 60 seconds to the minute for timing purposes. To obtain various periods of motion and rest or timing, teeth are cut away in two parts of the circumference, and other portions of the circumferences have the addendum portion of the teeth cut away to 25 the pitch line and made convex in form, in the case of the index wheels.

As regards the pinion it also has teeth 30 cut away in parts of its circumference, whilst the remaining parts of the circumference have the addendum portion of the teeth cut away to the pitch line diametrically opposite to each other, with a portion of their circumference formed concave.

With this construction, when the apparatus 35 is rotating, the portion of the index wheel registers with the concave portion of the pinion, and causes the pinion to rest or remain idle until the toothed portion of the wheel comes in contact with the toothed portion of the pinion, when it moves it through one half of a revolution, this occurring each time the teeth mesh with each other.

The valves are opened through suitable 45 connecting rods co-operating in the preferred construction with toothed quadrant levers and pinions, the motion being transmitted in any suitable manner to the valves themselves.

In order that the invention may be readily 50 understood reference is made to the accompanying drawings in which:—

Fig. 1 is a diagrammatic view showing the general arrangement of the machine for treating cotton, wool or other fibers.

Fig. 2 is a sectional view showing the automatic gearing for effecting the periodic opening and closing of the base and product valves the section being taken through the line 2—2 Fig. 3. Fig. 3 is a sectional plan 55 of Fig. 2 taken on the line 3—3 of that figure.

Fig. 4 is a transverse view, partly in section, the sectional upper portion of the figures being taken at line 4—4 of Fig. 2.

Fig. 5 is a view to an enlarged scale show-

ing one of the toothed index wheels and the pinion wheel associated therewith.

The machine for treating cotton, wool and other fibers is indicated diagrammatically in dotted lines at *a*, the feed hopper being indicated at *b*, the treating chamber at *b*¹, and *b*² indicates the path of rotation of the beater. The automatic controlling apparatus for the base and product valves is enclosed in an air tight casing or magazine *c* located in the neighborhood of the top of the machine. Within this casing, is a shaft *d* rotatably mounted in bearings *c*⁴. One end of the shaft has keyed thereto a stepped pulley *e* driven by a belt from the main shaft of the machine or from some other appropriate source of power. Extending parallel with the shaft *d* and supported in bearings is a shaft *s* to which are keyed a series of various sized externally toothed wheels *f* *f*¹ *f*²—*f*⁵. The opposite end of the shaft *s* carries a worm *g* meshing with a worm wheel *h* carried by a shaft or spindle *i* supported in bearings *c*² in the sides of the casing. The worm wheel extends within an oil bath *c*⁶ and is provided at opposite sides with a laterally extending boss or sleeve *h*¹ *h*² and on each of these bosses is mounted a disc or wheel *k* engaging a disc or wheel *l* mounted on a spindle or shaft *m* supported in bearings *c*³ in the sides of the casing. The wheels or discs *l* *l* are suitably keyed to their shaft *m*, so as to rotate therewith.

Mounted on the shaft *d* is a pivotal bracket or lever *o* one end of which carries an idle pinion *p*, adapted, when said lever *o* is slidden axially along the shaft *d* to mesh with either of the toothed wheels *f*—*f*⁵. The idle pinion *p* is in constant mesh with a toothed pinion *n* located between the forked sides of the bracket *o* and slidably keyed to the shaft *d*, so as to rotate therewith. The bracket or lever *o* carries an extending arm *o*¹ provided with a perforation *o*² and this perforated end of the arm *o*¹ is adapted to engage steps *q* (Fig. 3) by means of which said arm is positioned, the arm being secured in the desired position by a pin *q*¹ passing through the perforation in the arm and engaging corresponding recesses in the step. The steps are arranged in such a manner as to maintain the idle pinion *p* in engagement with one of the toothed wheels *f* *f*¹—*f*⁵ according to the position of the bracket *o*, the latter being rocked and its arm engaged with the corresponding step *q*.

The casing *c* is provided with a preferably hinged door *c*⁵ located adjacent the slideable bracket *o*, so as to permit adjustment thereof, when desired.

In order to effect the periodic opening and closing of the base and product valves, the shaft or spindle *m* to which the toothed pinions *l* are keyed, is provided at its outer

ends with discs, or wheels r r^1 , the disc r having a crank pin r^2 connected to one end of a rod 1, the opposite bifurcated end of which embraces one end of a longitudinally slotted lever 2 and is adjustably connected thereto by a pin or bolt. The lever 2 is mounted on a pivot 3 and at its opposite free end has formed therewith or mounted thereon a toothed quadrant 4 engaging a toothed pinion 5 mounted on a shaft 6. The shaft 6 carries a belt pulley which is connected to a second pulley 7 by a belt 8. The pulley 7 is mounted on a shaft 9 carrying a second pulley which drives by means of a belt 10 and ratchet and pawl mechanism (not shown) a shaft 11 on which is mounted a wheel 12 provided with a series of blades or radial arms 13 projecting into the feed 20 hopper b and arranged to be periodically rotated in one direction, so as to control the passage of the base under treatment to the cleaning machine a . The ratchet and pawl mechanism is so arranged as to cause the shaft 11 to partially rotate in one direction each time the rod 1 is reciprocated.

The other disc r^1 also carries a crank pin r^3 which is pivotally connected to one end of a rod 14, the opposite forked end of which is connected to a second slotted lever 15 mounted on a pivot 16, the toothed quadrant 17 on the opposite end of this lever engaging a toothed pinion 18 on a shaft 19 connected to and adapted to operate by any suitable means the product valve shown in the open position by dotted lines at 25 toward the bottom of the machine the path of closing of the valve 25 being indicated by broken lines at 26.

40 The product valve is operated through a trip motion or by means of a ratchet and pawl, so that as the product valve is closing the base valve gear will come into operation to open the valve, by this means preventing loss of time between the closing of the product valve and the admission of a new charge of base.

The shaft 19 also carries a pulley or drum 50 20 to which is secured one end of a chain, band or belt 21, the opposite end of which passes over a roller 22 carried by a bracket 23, the opposite end of the chain or belt 21 carrying a series of balance weights 24.

55 It will thus be seen that the rotation of the shaft m causes both the base and product valves to be independently and alternately opened and closed. In order to effect the periodic opening and closing of the valves, the index wheels k and the wheels or discs l are each provided with teeth extending over portions of their peripheries, as shown in Fig. 5.

The index wheels k have portions v^1 and 65 v^2 of their peripheries formed with teeth

whilst the remaining portions of said wheels are cut away to a point representing the pitch circle of said wheels, as shown at v^0 and t in Fig. 5. The wheels or discs l are each formed with teeth l^1 extending over two sectors, the portions of the periphery of each wheel between the ends of these sectors being cut away to form concave recesses l^2 l^3 the bottom of which corresponds with the pitch circle of said wheels whilst the radius of the concave recesses correspond to the radius of the pitch circle of the wheels k .

As previously described the wheels k are each rigidly mounted on laterally extending bosses h^1 on opposite sides of the worm wheel h , so that each of the wheels k rotate therewith. It will thus be seen that on rotation of the wheels k , the shaft m will be periodically or intermittently rotated at appropriate times but always in the same direction. Assuming the wheels k and l , shown in Fig. 5 to be operatively connected to the base valve it will be seen that with the wheel k rotating in the direction indicated by the arrow, the valve controlling the admission of the material to the machine is just about to open, the teeth v of the wheel k on the sector v^1 about to engage the teeth l^1 on the wheel l , thereby rotating the shaft m causing the operating rod 1 to be reciprocated to operate the valve to the fully open position, the cut away portion represented by the sector v^0 of the wheel k now registers with the concave recess l^2 of the wheel l so that the rotation of the shaft m is stopped the base valve remaining fully open during the rotation of the wheel k through a distance represented by the sector v^0 . On the forward end of the toothed sector v^2 of the wheel k reaching the periphery of the wheel l , the latter is again brought into mesh and the shaft m will again be rotated until the valve is closed, and during the further rotation of the wheel k through the sector t the valve will remain closed, this period corresponding to the time during which the material is under treatment in the machine a . The index wheel k controlling the product valve 115 operates in a similar manner, the gearing being arranged to operate each valve independently at the appropriate times.

It will thus be seen that the opening and closing of the base and product valves is entirely automatic whilst the time of opening and closing of the valves and the time during which the material is under treatment in the machine, may be varied as desired according to the speed of rotation 120 of the shaft s , the driving shaft d being driven at a constant speed, whilst the relative speed of the shaft s may be varied by the rocking and axial adjustment of the bracket o as previously described.

The pinions 77 instead of being connected together may, if desired, be each rigidly connected to or formed in one with the discs or wheels r r' , respectively, so that the rotation of the discs may be timed to open and close the valves for the base and product at appropriate times, the teeth on the pinions or on the index wheels being respectively displaced to effect this independent operation.

It will be understood that the particular construction just described is given merely by way of example, and that the details of construction may be modified to suit the type of machine to which the invention is applied, without departing from the principle of the invention.

What I claim as my invention and desire to secure by Letters Patent of the United States of America is:—

1. A machine for opening and cleaning cotton, wool and other fibers, comprising in combination, a treating chamber, a beater shaft rotatable in said chamber a feed hopper through which the material is fed into said chamber, a discharge valve through which the treated product is delivered, a shaft carrying a worm and driven through variable transmission gearing from a source of power, a worm wheel in constant mesh with said worm, discs mounted adjustably on said worm wheel each having a segmental rack, a disc also having a segmental rack

cooperating with each of said first mentioned discs and adapted to be intermittently rotated thereby, and means associated with said second mentioned discs connected by links and levers to each of said valves, substantially as described.

2. A machine for opening and cleaning cotton, wool and other fibers comprising in combination a treating chamber, a beater shaft rotatable in said chamber, a feed hopper through which the material is fed into said chamber, a discharge valve through which the treated product is delivered, a shaft carrying a worm and driven through variable transmission gearing from a source of power, a worm wheel in constant mesh with said worm, a pair of discs mounted adjustably on said worm wheel each having teeth over a portion of its periphery a pair of discs of smaller diameter mounted adjacent said first mentioned discs and each having teeth over a portion of their periphery adapted to mesh with the teeth of the corresponding disc on the worm wheel a crank arm associated with each of said smaller discs, links connected at one end to said crank and at the other end to one end of a fulcrumed lever carrying a toothed sector, and pinion wheels engaging said toothed sectors adapted to positively operate the base and product valves respectively during their opening and closing movement.

WILLIAM YOULTEN.
